A. E. RIPLEY

PERFORATING ATTACHMENT

Filed June 6, 1921

Patented June 16, 1925.

1,542,097

UNITED STATES PATENT OFFICE.

ALBERT E. RIPLEY, OF BAY CITY, MICHIGAN.

PERFORATING ATTACHMENT.

Application filed June 6, 1921. Serial No. 475,302.

To all whom it may concern:

Be it known that I, ALBERT E. RIPLEY, a citizen of the United States of America, and a resident of Bay City, in the county of Bay 5 and State of Michigan, have invented certain new and useful Improvements in Perforating Attachments, of which the following is a specification.

This invention relates to perforators for 10 perforating paper and the like, and particularly to perforators such as used in printing shops where a large amount of this perforating work is required to be done.

One object of the invention is to design 15 a very simple, durable and economical perforating attachment which can be quickly and easily attached to a printing press, but which is particularly designed to be attached to the commercially named "Kelly press."

Another object of the invention is to design 20 an adjustable perforating attachment which can be easily adjusted to suit different weights of papers, and which will form a neat and clean perforation.

With the above and other objects in view, the present invention consists in the combination and arrangement of parts, hereinafter more fully described, illustrated in the accompanying drawings, and particularly 25 pointed out in the appended claims, it being understood that changes may be made in the form, size, proportion and minor details of construction, without departing from the spirit, or sacrificing any of the advantages 30 of the invention.

In the drawings:

Fig. 1 is a fragmentary view of the rear 35 end of a commercially named "Kelly press" illustrating my improved perforating attachment in place thereon.

Fig. 2 is a cross sectional view of one of the perforating heads.

Fig. 3 is an enlarged front view of one 40 of the perforators and grooved rollers, and

Fig. 4 is a side view thereof.

Referring now particularly to the drawing 45 in which I have shown the preferred embodiment of my invention. The frame of the press I have indicated by the numeral 1, this can be of any suitable construction, and is provided with standards or uprights 2 rigidly secured to the said frame, a transversely disposed bar 3 being detachably secured to the upper ends thereof. A gear 50 casing 4 is secured to the side of the press, and is adapted to house a train of gears

(not shown) for driving the transverse shaft 5 which is journaled in the hub 6 rigid on the frame, rearwardly extending arms 7 being formed integral with this hub, and a 60 similar transverse shaft 8 is revolvably journaled in the free ends of these arms.

A series of rollers 9 are securely mounted 65 on this transverse shaft 5 in spaced relation with each other, and a groove 10 is formed in the face thereof for a purpose to be presently explained; a second groove 11 is also formed in the face near one edge of the roller, and a round belt 12 is adapted to travel therein, leading rearwardly and 70 traveling in a similar groove formed in the roller member 13 mounted on the shaft 8; in practise the top of this belt projects slightly above the face of the rollers, and as the stock is printed, it travels towards the 75 rear of the machine over these rollers 9, and is engaged by the belts 12 which carry it through as clearly shown in Fig. 1 of the drawing, the stock being indicated by the numeral 14 and is printed before it is engaged by the belts 12.

In certain instances it is necessary that 80 this stock be perforated in order that certain parts can be readily detached, for instance the well known check which is usually attached to a stub; as these checks are used they are of course detached from the stubs, the perforation insuring that the stock will easily tear and part on a straight line. I am aware that there are a number 85 of perforating devices in use at the present time, but these are mostly very expensive, being built as an individual machine, requiring the services of an operator, to handle the stock and feed it through the perforating machine. My improved attachment 90 eliminates the service of the operator and saves the time required for feeding it through the machine, as the stock is automatically perforated as it travels through 100 the press, and in no way interferes with the printing.

The bar 3 is secured to the uprights 2 by means of the bolts 15, an elongated slot 16 being formed therein, and a head 17 embraces the said bar as shown; a bolt 18 extends through this head, the upper end being threaded to receive a nut 19 in the usual manner, and a shoulder 20 is formed intermediate the length of this bolt, the lower end 110 being bent at a right angle and on which is revolvably journaled the perforating wheel

21; this wheel has a comparatively wide face, and is formed with a plurality of relatively small perforating teeth 22 integral therewith which are adapted to pierce the 5 stock feeding beneath it. A coiled spring 23 is interposed between the shoulder 20 and the bottom of the head, and it will be obvious that by manipulating the nut 19 any desired adjustment can be secured to suit the 10 different weights of stock.

The head is secured to the bar 3 by means of a stud bolt 24 extending through the slot and threaded into a similarly threaded opening in the head, and lateral adjustment of 15 the perforators can be easily made by loosening this stud.

The perforating teeth 22 travels on the groove 10, but do not engage the sides or bottom thereof, and it will be apparent that 20 these teeth will not be easily dulled, further, the wide face of this perforating wheel prevents the stock from crinkling and clinging to the perforating teeth, obviating the necessity of a stripper.

To prevent the bolt 18 from turning in the head a dowel 25 is secured thereto, the free end extending through a slotted opening 17^a formed in the head.

Considerable care is required in the adjusting of these perforating rollers to suit the stock, and to insure this adjustment being maintained when secured, I provide a small spring member 26 which I secure to the back of the head by means of a screw 27; this spring extends upwardly and bears 35 against the nut 19 to prevent its turning, or slots may be cut in the nut to receive the said spring if desired.

In the present instance I have shown the 40 perforating teeth integral with the wheel, but it will be readily understood that the teeth can be formed on a relatively thin disk and a roller with a face of suitable width can be secured on either side thereof, and this

construction is within the spirit of my invention. 45

From the foregoing description it will be obvious that I have perfected a simple, and efficient perforating attachment for presses, which will make a very neat and clean perforation and which can be quickly attached to a printing press.

What I claim is:—

1. The combination with a printing press having a pair of spaced apart brackets 55 mounted thereon, a longitudinally slotted bar connecting said brackets and detachably secured thereto, a plurality of heads slidably and adjustably mounted thereon, perforating means carried thereby and comprising relatively wide rollers having a plurality of small teeth formed thereon grooved, driven rollers beneath said perforating rollers and adapted to impart motion thereto and in which the said perforating teeth travel, and 60 means on the heads for maintaining a pressure on the perforating rollers for positively moving the stock over the grooved rollers.

2. The combination with a printing press having a pair of spaced apart brackets 70 mounted thereon, a longitudinally slotted bar connecting said brackets and detachably secured thereto, a plurality of individual perforating attachments slidably and adjustably mounted thereon and comprising wheels 75 having a plurality of perforating teeth formed therein, driven rollers beneath the perforating rollers, and adapted to impart motion to said wheels, grooves formed therein and adapted to receive the teeth of the 80 perforating rollers, means for exerting a pressure on the perforating rollers, and a plurality of means for continuously feeding and moving the stock to be perforated between the said rollers.

In testimony whereof I affix my signature.

ALBERT E. RIPLEY.
